Primary Examiner — Austin Murphy(74) *Attorney, Agent, or Firm* — Fish & Richardson P.C.(57) **CLAIM**

The ornamental design for a card reader, substantially as shown and described.

DESCRIPTION

FIG. 1 is a perspective view of the card reader.

FIG. 2 is a front view thereof.

FIG. 3 is a back view thereof.

FIG. 4 is right side view thereof.

FIG. 5 is left side view thereof.

FIG. 6 is top view thereof.

FIG. 7 is bottom view thereof.

FIG. 8 is a perspective view of the card reader attached to a dialysis machine and attached to a pole to support an intravenous (IV) fluid container. The dialysis machine is shown in dashed lines as a representation of environment and is not an element of the claimed design.

FIG. 9 is a right side view thereof; and,

FIG. 10 is a top view thereof.
